CLAIM

The ornamental design for a golf shoe outsole, as shown and described.

DESCRIPTION

FIG. 1 is a bottom perspective view of the golf shoe outsole showing our new design;

FIG. 2 is a left side elevational view thereof;

FIG. 3 is a right side elevational view thereof;

FIG. 4 is a bottom plan view thereof;

FIG. 5 is a rear elevational view thereof; and,

FIG. 6 is a front elevational view thereof.

The circular broken lines in FIGS. 1 & 4, define the boundaries of the design with the lines themselves and the areas within them forming no part of the claim. The trapezoidal shape on the arch, which is shown in broken lines, and appears behind a transparent surface represents the portion of the design that forms no part of the claim.
